HIGH FREQUENCY GENERATOR

Erich Habann, Berlin-Hessenwinkel, and Felix Gerth, Berlin-Tempelhof, Germany, assignors to C. Lorenz Aktiengesellschaft, Berlin-Tempelhof, Germany, a German company

Application August 22, 1936, Serial No. 97,394
In Germany August 24, 1935

7 Claims. (Cl. 250—36)

The invention relates to arrangements for producing high frequency oscillations by means of electron tubes of the kind having a split anode, that is, an anode made in two or more parts disposed in cylindrical relation to the glowing cathode or filament. Tubes or valves of this type have a magnetic field arranged to act along the axis of the anode and thus along the filament.

The invention has for its object to improve the mode of operating oscillation generators of this kind and in this connection also to improve the construction thereof, and will be understood from the following description, reference being had to the accompanying drawing in which

15 Fig. 1 is a partially perspective and partially sectioned diagrammatic view of an example of the novel arrangement. Fig. 2 shows a section on the line 2—2 of Fig. 3, Fig. 3 a section on line 3—3 of Fig. 2, both Figs. 2 and 3 disclosing improvements 20 upon the arrangement illustrated in Fig. 1. Fig. 4, drawn to a larger scale than Figs. 1 to 3, shows a section through one of the conductors of the oscillatory circuit or Lecher wire system of the electron tube and relates to an improvement upon 25 these conductors as represented in Figs. 1 to 3.

The electron tube 1 has an anode that consists of two cylinder portions 2. The cathode or filament 3 thereof is disposed in the axis of the cylinder 2. A source of current 4 serves to heat 30 the filament 3. The magnetic field acting along filament 3 is that of an electro-magnet 5. Connected in series with the current source 6 for magnet 5 is a variable resistance 7. To the anode parts 2 are fastened two metallic sheets 8 which 35 are interconnected by a bridge 9 adapted to be displaced between them. The arrangement 8, 9 is the oscillatory circuit or Lecher wire system of the tube 1. The anode voltage is supplied by a current source 10 which is connected to the middle of 40 the bridge 9 in the manner represented and is connected also to filament 3 over a variable resistance 11.

Tube 1 and Lecher wire system 8, 9 may be contained in a casing 12, as shown in Figs. 2 and 3. Casing 12 may have openings 13 opposite each other in order that air may be moved through the casing by a fan or blower 14, as indicated by the arrows in Fig. 3, the object being to cool the sheets 45 8. These may be provided with ribs 15 and may also consist of a core 16 and coatings 17 thereon, as illustrated in Fig. 4.

The means described herebefore may be employed either individually or conjointly and serve 50 as negative resistance for the oscillatory circuit or

Lecher wire system for a purpose stated herein-after.

The frequency of the oscillations generated by devices of this kind is determined substantially by the tuning system, the anode potential, the radius 5 of the anode cylinder and the strength of the magnetic field. These oscillations are defined by the formula

$$H^2 \cdot \frac{e}{m} = \frac{8V_a}{r_a^3} \quad (I) \quad 10$$

where H is the magnetic fieldstrength in gauss,

$$\frac{e}{m}$$

the ratio of the charge of an electron to the mass 15 thereof, V_a the anode potential and r_a the radius of the anode cylinder.

The fieldstrength defined by this formula is designated as the critical one. It is well known 20 that oscillations can arise with values of the field strength which are either below or above this critical value.

In addition to the fieldstrength defined by the Formula I there is still another critical fieldstrength, this being defined by the formula 25

$$H = \frac{10650}{\lambda \text{ cm.}} \quad (II)$$

where the magnetic fieldstrength H is expressed in gauss and the wavelength λ in centimetres. This 30 second field strength defines a rotational movement of the electrons with a certain rotational frequency within the discharging space in their cycloid shaped course with a certain rotational frequency corresponding to the number of the 35 rotational movements effected by the electron under the influence of the magnetic field strength. The rotational frequency of the electrons is independent of the speed of the electrons caused by the anode voltage and exists already at the start 40 speed, supplied to the electrons by the heat movement at the emission. In case the rotational frequency is equal to the natural frequency of the connected oscillatory circuit no oscillations will occur therein. This refers to the frequency 45 range of the generated oscillations, wherein the tube is used as negative resistance for the oscillation generation. If, for example, with a frequency of 3.10^4 kilocycles a wavelength of 10 metres is generated then about 100 gauss are 50 required. The rotational frequency in this case is 3.10^8 kilocycles.

It has now been found that far below this critical value of the magnetic fieldstrength, i. e. the value defined by the two Formulae I and 55

- II, that is to say with a relatively low anode potential, oscillations occur which have not been known so far. It has been experienced that there is a certain range of fieldstrength in which 5 no oscillations arise under ordinary circumstances, whilst predetermined conditions will cause special oscillations to originate and these are obtained only if the oscillatory circuit is to a high degree free of attenuation.
- 10 This novel range involves a great advantage inasmuch as it admits of reducing the voltages and magnetic fieldstrengths, which even in the case of short waves are extremely high, to such extent that devices of this kind need not be given 15 dimensions so small that the devices are difficult to handle. For instance, larger tube diameters may be employed in cases that otherwise require extremely small diameters to be employed. The rotational frequency is other than the produced 20 frequency, being greater than this. If the magnetic fieldstrength is reduced to a small value so that the rotational frequency will be in the neighbourhood of the produced frequency, this frequency being determined by the oscillating 25 circuit of the tube, then the oscillations will cease after having decreased quickly in energy. It is not possible to generate oscillations within a range in which the rotational frequency and the frequency to be generated accord with each 30 other.

The invention is based on the supposition that the rotational frequency should not be considered a commencement as regards frequencies which may perhaps be obtainable, but that the rotational frequency only forms a gap in the range 35 of oscillations. With smaller fieldstrengths oscillations will originate again, namely oscillations of a frequency higher than is the rotational frequency. Such oscillations however only 40 arise if the attenuation of the oscillating circuit of the tube is extremely small.

In order that this oscillatory circuit be sufficiently free of attenuation, with a view to making accessible said range, the sheets 8 are attached to the anode members 2 in the manner 45 before described, so as to take the place of the customary Lecher wires. Also, for diminishing the attenuation of the oscillation circuit it is suitable to cool the sheets 8 so as to avoid a rise 50 in the temperature thereof caused by the currents. For instance, the sheets may be acted upon by an air current produced by the fan or blower 14 in the manner before stated. The described ribs 15 will assist the air current in 55 its cooling action. Instead of the fan 14 any other suitable device may serve to produce the air current for cooling. Further, the cooling action is aided by a certain thickness of the sheets 8 and also by the provision of the coatings 17 as 60 described with reference to Fig. 4, these coatings consisting of a metal of high electric conductivity, such as silver. In this case also the thermal conductivity is very great so that any heat will be quickly led away. Finally, attenuation 65 effects may be obviated by avoiding radiation as far as possible. In order to perform this a casting such as 12 may be provided.

It is to be understood that these embodiments of the invention may be modified without departing from the spirit of the invention. For instance, the anode of the tube 1 may consist of more than two parts, for example of four parts, and any cooling means other than those described may be used. 5

What is claimed is:

1. In an arrangement for generating high frequency oscillations, an electron tube having a split anode, a cathode symmetrically surrounded by said anode, an oscillation circuit connected with said electrodes, means to produce along said cathode a magnetic field whose intensity expressed in gausses is below the value 10

$$\frac{10650}{\lambda \text{ cm.}}$$

wherein λ is the wave length, and by which value the rotational frequency of the electrons is determined, means to decrease the anode potential to such a low value that the rotational frequency of the electrons will be less than the frequency of said oscillation circuit, and means for reducing the attenuation of said circuit to such an extent that oscillations will be produced which will be of higher frequency than those that would be produced by adjusting said field intensity of the tube to a value higher than said value 20 25

$$\frac{10650}{\lambda \text{ cm.}}$$

30

the circuit being tuned to said higher frequency.

2. An arrangement according to claim 1 wherein said means for reducing the attenuation comprises metallic sheets constituting the 35 conductors of said oscillation circuit.

3. An arrangement according to claim 1 in which said means for reducing the attenuation comprises metallic sheets constituting the conductors of said oscillation circuit, and in 40 which means are provided for cooling said sheets.

4. An arrangement according to claim 1 wherein said means for reducing the attenuation comprises metallic sheets constituting the conductors of said oscillation circuit, and 45 cooling ribs provided on said metallic sheets.

5. An arrangement according to claim 1 wherein said means for reducing the attenuation comprises metallic sheets constituting the conductors of said oscillation circuit, and 50 means for producing air currents to cool said sheets.

6. An arrangement according to claim 1 wherein said means for reducing the attenuation comprises metallic sheets constituting the 55 conductors of said oscillation circuit, and a coating of very great electrical conductivity on said sheets.

7. An arrangement according to claim 1 and in which said means comprises metallic 60 sheets constituting the conductors of said oscillation circuit, and a coating of silver on said metallic sheets.

ERICH HABANN.
FELIX GERTH.
